United States Patent Office

Des. 217,339
Patented Apr. 28, 1970

217,339

BUILDING

Bradley V. Sims, Laguna Niguel, Calif., assignor to Country Boys Market Corporation, Laguna Beach, Calif., a corporation of California

Filed Oct. 14, 1968, Ser. No. 13,993

Term of patent 14 years

Int. Cl. D25—04

U.S. Cl. D13—1

FIG. 2.

FIG. 5.

FIG. 1 is a perspective view of a building embodying my new design;

FIG. 2 is a top plan view of the building;

FIG. 3 is a side elevational view of the building as viewed from the left in FIG. 1;

FIG. 4 is a rear elevational view of the building;

FIG. 5 is a front elevational view of a second embodiment of the invention corresponding to that of FIG. 1 except as disclosed;

FIG. 6 is a rear elevational view of a third embodiment of the invention, corresponding to the embodiment shown in FIG. 4 except as disclosed;

FIG. 7 is a side elevational view of the third embodiment, corresponding to the embodiment of FIG. 3 except as disclosed.

I claim:

The ornamental design for a building, as shown and described.
